UNITED STATES PATENT OFFICE.

GEORGE W. FRAZIER, OF ALLEGHENY, PENNSYLVANIA.

ELECTROLYTIC WATER-PURIFIER.

SPECIFICATION forming part of Letters Patent No. 741,322, dated October 18, 1903.

Application filed January 3, 1903. Serial No. 137,633. (No model.)

To all whom it may concern:

Be it known that I, GEORGE WASHINGTON FRAZIER, a citizen of the United States, residing at Allegheny, in the county of Allegheny and State of Pennsylvania, have invented certain new and useful Improvements in Electrolytic Water-Purifiers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to electrolytic water-purifiers, and belongs to that class of apparatus built for the purpose of precipitating from water by means of current electricity the solid matter, whether organic or otherwise, held in solution or mechanically suspended by the fluid.

The object of my invention is the production of an electric purifier wherein the parts are of special construction and arrangement by means of which all the metal of the electrodes may be consumed without waste as the process of purification proceeds; and it is also an object of my invention to provide a purifier most easily taken apart or set up and composed of elements possessing the simplest practicable forms and least number, thereby rendering it unnecessary to change the design of the invention no matter what the required size may be.

35 I attain the stated object by the employment and association of parts, as illustrated in the accompanying drawings, of which—

Figure 1 is a vertical mid-section, and Fig. 2 a top plan, of the contact disks or plates. Fig. 3 represents a plan view of the insulating-cross that is situated between the electrodes, the scale of drawing being reduced in this figure.

Like numerals refer to like parts throughout.

45 Considering the drawings, numeral 1 marks the casing-tube, made of glass to permit a view of the interior or formed of metal for strength. The heads are designated by numbers 2 and 3, and they usually have the annular grooves 4 and 5 fitting the edges of the tube and containing gaskets or packing-rings

6 and 7, of suitable substance. Bolt-rods 8 and 9, of which there may be any number, clamp the heads and tube together. The 55 heads have threaded centrally-located throats 10 and 11 for connection with water-pipes to and from the apparatus. Head 2 has the additional threaded openings 12 and 13, closed by the insulating screw-plugs 14 and 15. Projecting from the tops of plugs 14 and 15 are 60 conducting binding-screws 16 and 17, engaging nuts 18 and 19, and axially through the plugs the conductors 20 and 21 pass and are secured. Wires from any suitable source of 65 electricity are connected with the apparatus by means of the nuts and binding-screws mentioned. Conductor 20 has its end within the tube in metallic connection with the contact plate or disk 22, shown as resting on 70 an insulating-ring 23 upon the head 3. There are two contact-disks, and they may be duplicates. The second disk at the top of the apparatus is marked 24, and both have vertical flanges, referred to by numbers 25 and 75 26. The lower disk 22 forms a seat for the electrode 27, which is pierced by an axial passage 28, through which water passes upwardly against the bottom of the complementary companion electrode 29, where it spreads outwardly in all directions and finds a final outlet at the upper throat 10. Electrode 29 is a cylindrical block, and upon it and in metallic contact with it is the contact-disk 24, already mentioned. The flanges of the disks 80 25 prevent their displacement with respect to the electrodes. Immediately between the electrodes and preventing actual contact one with the other is the insulating-cross 30, and at the extremities of its arms will be noted 90 the buttons 31, the office of which is to prevent the electrodes from contact with the conductors 20 and 21 at undesired points. Each contact-disk is formed usually with a lug at one side. (See Fig. 2.) The lug on disk 22 95 is marked 32, and that on disk 24 is 33. The conductors make contact with the disks by way of the lugs. Conductor 20 has a fixed connection with lug 32, while conductor 21 passes down through lug 33 and is grasped 100 by two spring-fingers 34 and 35, which maintain a constant and sufficient electrical contact, yet allow the descent of electrode 29 as it is consumed by the electrochemical action,

or if the lower electrode be the one more rapidly eaten away by electrical action the descent of the upper electrode is thus permitted, and the distance between the electrodes is 5 caused to remain uniform, and therefore the electrical resistance of the device is kept constant.

Numbers 36 and 37 mark the central orifices through contact-plates 22 and 24, corresponding in position and size to the passage 10 28 through the lower electrode 27.

I prefer to constitute the electrodes of aluminium and the contact-disks and conductors of heavily silver-plated metal. Silver is practically unaffected in the presence of aluminium by the action of current electricity, and it is desired that the disks and conductors be renewed as infrequently as possible for obvious reasons of expense and trouble of 15 curing new ones. My invention takes advantage of the peculiar natural or chemical property of the hydrated oxid of aluminium formed. This compound of the metal in water coagulates, collects, and throws down as 20 25 an insoluble precipitate animal impurities suspended in a minutely-divided state. Nascent oxygen evolved freely attacks and oxidizes vegetable impurities, and any uncombined oxygen remains in the water, imparting thereto a sparkling quality rather beneficial and agreeable than otherwise, the gas resembling ozone in its effects. The hydrogen generated electrically being chemically active, as is usual, seeks the oxygen of any 30 35 mineral or earthy salts in the water and deposits the metal. After passing through my invention the water is conducted into a suitable settling-basin or led to a filter, and the collected and coagulated impurities are 40 45 wholly removed. The peculiar chemical and physical effects upon the water while passing through my invention have been found to render subsequent settling or filtration vastly more thorough than would be possible without the treatment described, and the percentage of remaining micro-organisms is reduced to a minimum.

Usually the lower electrode 27 constitutes the anode of my invention; but that is not obligatory, and the current may be reversed in direction. Furthermore, I have found that an alternating current of suitable voltage and sufficient quantity will purify water passed through my invention. In practice it is sometimes advantageous to use more than one purifier arranged either one above another or in series, the water passing from one to another.

I am aware that numerous electrolytic water-purifiers have been constructed and that aluminium electrodes have been employed, and I do not claim those features broadly.

What I claim, and seek to secure by Letters Patent, is—

65 1. In an electrolytic water-purifier, the combination of the casing having removable heads provided with water-pipe connections, a lower

contact-plate and a conductor connected thereto and leading out of the casing, a lower electrode resting upon said contact-plate, an 70 upper electrode above the said lower electrode and an insulating-piece between the electrodes, an upper contact-plate resting on the upper electrode, means adapted to direct water between the electrodes, a second conductor leading out of the casing, and devices whereby a constant connection is maintained between the upper contact-plate and said second conductor and permitting an up or down movement of the plate, substantially as described. 75 80

2. In an electrolytic water-purifier, the combination of the casing having removable heads provided with water-pipe connections, a lower contact-plate having a circumferential perpendicular flange, a conductor connected to said plate and leading out of the casing, a lower electrode resting on said contact-plate, an upper electrode above the said lower electrode, a cross of insulating material arranged between 85 the electrodes and the arms of the cross having terminal buttons, an upper contact-plate resting on the upper electrode and having a circumferential perpendicular flange, means adapted to direct water between the electrodes, a second conductor leading out of the casing, and devices whereby a constant connection is maintained between the upper contact-plate and said second conductor permitting an up or down movement of the plate, 90 substantially as described. 95 100

3. In an electrolytic water-purifier, the combination of the casing having removable heads and provided with water-pipe connections, a lower contact-plate having a central orifice, a conductor connected with said plate and leading out of the casing, a lower electrode resting upon the plate and having a central passage corresponding to the orifice of the plate, an upper electrode above the said lower electrode and an insulating-piece between the said electrodes, the pipe connection in the lower head also corresponding to the orifice of the said plate and directing water through the plate and electrode causing it to pass between the electrodes, an upper contact-plate resting on the upper electrode, a second conductor leading out of the casing, and devices whereby a constant contact is maintained between the upper contact-plate and said second conductor permitting an up or down movement of the plate, substantially as described. 115 120 125

4. In an electrolytic water-purifier, the combination of the casing having removable heads and provided with water-pipe connections, a lower contact-plate having a silver surface and a central orifice, a conductor connected with said plate and leading out of the casing, a lower aluminium electrode resting upon the plate and having a central passage corresponding to the orifice of the plate, an upper aluminium electrode above the said lower electrode and an insulating-piece between the said electrodes, the pipe connection in 130 135

the lower head also corresponding to the ori-
fice of the said plate and directing water
through the plate and electrode causing it to
pass between the electrodes, an upper con-
5 tact-plate having a silver surface and resting
on the upper electrode, a second conductor
leading out of the casing, and devices where-
by a constant contact is maintained between
the upper contact-plate and said second con-

ductor permitting an up or down movement to
of the plate, substantially as described.

In testimony whereof I affix my signature
in presence of two witnesses.

GEORGE W. FRAZIER.
